UNITED STATES PATENT OFFICE

SAMUEL L. POMERANTZ, OF BROOKLYN, NEW YORK

DESIGN FOR A LOOSE POWDER SIFTER BOX

Application filed June 8, 1931. Serial No. 40,120. Term of patent 3½ years.

To all whom it may concern:

Be it known that I, SAMUEL L. POMERANTZ, a citizen of the United States and resident of Brooklyn, in the county of Kings and State of New York, have invented a new, original, and ornamental Design for a Loose Powder Sifter Box, of which the following is a specification.

In the accompanying drawing:

Fig. 1 is a plan view of a loose powder sifter box showing my design, and

Fig. 2 is a side elevational view of Fig. 1.

The dominant feature of my design is the arrangement of configurations representing the surface of a golf ball applied on the top and bottom of the box.

I claim:

The ornamental design for a loose powder sifter box as shown and described.

Signed at New York, in the county of New York and State of New York this 26th day of May A. D. 1931.

SAMUEL L. POMERANTZ.
